E. B. TOWLE.

SPOON OR ANALOGOUS ARTICLE.

No. 15,421.

Patented Sept. 16, 1884

UNITED STATES PATENT OFFICE.

EDWARD B. TOWLE, OF NEWBURYPORT, ASSIGNOR TO THE JOHN RUSSELL CUTLERY COMPANY, OF TURNER'S FALLS, MASSACHUSETTS.

DESIGN FOR A SPOON OR ANALOGOUS ARTICLE.

SPECIFICATION forming part of Design No. 15,421, dated September 16, 1884.

Application filed June 21, 1881. Term of patent 7 years.

To all whom it may concern.

Be it known that I, EDWARD B. TOWLE, a citizen of the United States, residing at Newburyport, in the county of Essex and State of Massachusetts, have invented and produced a new and original Design for a Handle for a Spoon or Analogous Article, of which the following is a specification, reference being had to the accompanying photograph, forming a part thereof.

The photograph shows a plan view of a spoon having my newly-designed handle, said view being sufficient to fully illustrate my design, which consists in the ornamentation on the upper or more exposed surface of the handle. That part, A, of the surface at the outer end of the spoon-handle, shaped as shown, has in relief thereon the representation of a swan resting on water. A space, B, of the surface toward the bowl of the spoon from the part A forms the "shield," the same presenting a hammered surface—that is, a surface having irregular depressions, such as may be made by means of a suitable hammer. The shank C of the handle has scroll-work thereon, as shown. There is a molding, a, in lines transverse to the length of the handle, between that part of the surface on which is the swan and that part

displaying the shield, and a similar molding, b, between the shield and the surface of the shank covered by the scroll-work.

The leading features of the design are the swan on that part of the surface at the outer end of the handle, the hammered surface to form the shield, and the scroll-work on the shank, the handle having the configuration shown, being widest at or near the outer end and tapering toward the shank. A handle having my design is suitable not only for a spoon, but also for an analogous article—such as a knife or fork.

I claim—

The design for the handle of a spoon or analogous article, having the configuration and ornamentation shown and described, the same consisting of a representation of a swan resting on water on that part of the surface at the outer end of the handle, the shield presenting the hammered surface and the scroll-work on the shank, the handle being widest at or near the outer end and tapering toward the shank.

EDWARD B. TOWLE.
